Application August 25, 1943, Serial No. 499,980

3 Claims. (Cl. 251—8)

This invention relates to valves and more particularly to screw-actuated plug valves.

An important object of the invention is to provide a valve, free of the usual packing or stuffing box about the valve stem, free of leakages at the juncture of the bonnet and exterior portion of the actuating means and free of projections, other than an actuating handle, which handle forms an integral part of the valve housing.

Another important object is to provide a valve wherein temporary vacuums are not created, which vacuums may result in the slow drip of water after a valve is closed.

Still another object is to provide a valve on which moisture is not apt to condense, since a considerable portion of the interior surface of the valve housing is free to the atmosphere.

Another object is to provide novel means for reciprocating the valve element, the latter being free of attachment to this means, but carried thereby.

Yet another object is to provide valve elements of various forms adapted for use in this novel valve.

Other objects and advantages of this invention will be apparent during the course of the following detailed description, taken in connection with the accompanying drawings and in which drawings:

Figure 1 is a side elevation of the novel valve.

Figure 2 is a front elevation thereof.

Figure 3 is top plan thereof.

Figure 4 is an enlarged vertical longitudinal section of the novel valve, closed.

Figure 5 is a top plan of a valve seat.

Figure 6 is a top plan of a means for retaining the valve seat of Figure 5.

Figure 7 is an elevation and Figure 8 a top plan of a stationary body cooperating with the movable portions of the valve actuating means.

Figure 9 is a top plan of a washer, associated with the body of Figures 7 and 8.

Figure 10 is a side elevation, Figure 11 a top plan and Figure 12 a vertical section of a movable portion of the valve actuating means.

Figure 13 is a perspective view of a flow breaker which may be employed.

Figure 14 is a vertical longitudinal section, somewhat similar to Figure 4 but showing the valve open and a modified form of a movable portion of valve actuating means, differing from that shown in Figure 12, which modified form is also shown in Figures 15 and 16.

Figures 17, 19, 21 and 24 are elevations of

modified forms of valve elements which may be employed in this novel valve.

Figure 18 is a top plan of the valve element of Figure 17.

Figure 20 is a view partly in vertical section of the valve element of Figure 19.

Figure 22 is a view partly in vertical section of the valve element of Figure 21, and Figure 23 is a top plan thereof.

Figure 25 is a view partly in vertical section of the valve element of Figure 24, and Figure 26 is a top plan thereof.

In the drawings, wherein for the purpose of illustration are shown preferred and modified forms of the invention, the letter A may designate the valve housing; B the valve seat; C valve actuating means including the means shown in Figures 1, 10, 11 and 12; D modified valve actuating means of Figures 14, 15 and 16; E, F, G, H, K, L and M valve elements.

The valve housing A includes an upper stationary housing portion 30, from which may extend a hollow stem 31 for attachment, as by the screw threads 32 at one end, to a suitable source of liquid supply. There is a liquid inlet 33 between the portion 30 and stem 31 and its axis may be normal to the major axis of the portion 30. The chamber 34 within the portion 30 is provided with a downwardly facing substantially

30 V-shaped, circular groove 35 for retaining the valve seat B against vertical movement, as is apparent in Figure 4, and there is provided a second downwardly opening circular groove 36 which is formed between an outer depending skirt 37 of the portion 30 and a depending cylindrical section 38 of the portion 30, spaced inwardly of the skirt 37. This groove 36 is quite deep, as is apparent in Figures 4 and 14, and its purpose will be subsequently explained. From its lower end upwardly for a short distance, the interior face of the cylindrical section 38 is provided with screw threads 39. Preferably, the skirt 37 is shorter than the section 38. If desired, a depending spring-retaining boss 40 may project from the uppermost wall of the portion 30 with its axis aligning with the major axis of the portion 30.

This valve housing A also includes a lower movable housing portion or bonnet 45. This portion 45 is adapted to rotate and to move, when rotated, either upwardly or downwardly (i. e. the lower portion 45 telescopes with the upper portion 30). The upper end of the lower movable portion 45 comprises a cylindrical extension 46 which fits into the groove 36 and the fit is, pref-

55

erably, not a tight one. It will be noted that the upper end of the extension 46 does not touch the bottom or base of the groove 36. Below this extension 46, the wall of the housing portion 45 tapers downwardly and inwardly to form a nozzle 47, providing a liquid outlet, but this outlet is subordinate to the main liquid outlet later described. Above the subordinate outlet one or more recesses 48 may be provided in the wall of the portion 45 for a purpose later described. Otherwise, this wall is provided with interior screw threads 49 for association with a valve element support means next to be described.

The valve element support means includes a tubular member 50 comprising an upper tube section 51 and lower tube section 52. In both forms shown in Figures 4, 10, 11 and 12, as well as Figures 14, 15 and 16, this means 50 has in the upper section 51 a substantially flat top surface 53, affording a face-to-face contact with the bottom of the valve element head, with a circular opening 54 communicating with the passageway 55 through the section 51 and one or more circular openings 56 are provided in the side walls of the section 51, preferably just below the top surface 53 for the passage of liquid, into the passageway when the valve is open. The lower tube section 52 has a passageway 57 in communication with a passageway 55, a liquid outlet or opening 58 at its lower end, which outlet is the main outlet of the valve, and is exteriorly screw threaded, at its upper end, preferably with a square thread, as at 59. Below this thread, the periphery of the section 52 is smooth as at 60 and below this smooth face, there is a screw threaded portion, as at 61 which ends short of the lower end 62 of section 52, which end 62 is of reduced circumference and smooth. While the form shown in Figures 4, 10, 11 and 12 is of one-piece construction, the form shown in Figures 14, 15 and 16 is desirable where adjustment of the length of the tubular member is important. In this modification, the upper tube section is longer and indicated as 63, is adapted for separation from the lower tube section, indicated as 64, has exterior screw threads 65 and may have aligning screw driver slots 66 at its lower end. The only change in the lower tube section 64 is the provision of interior screw threads 67, cooperating with the screw threads 65 so that by inserting the section 63 into the top 68 of the section 64, and rotating it to the desired height, it may be substituted for the one-piece tubular member 50. The modified form of Figures 14, 15 and 16, together with the lower movable housing portion 45, constitute the modified valve actuating means D, while the form of Figures 4, 10, 11 and 12, together with the lower movable housing portion 45, constitute, of course, the valve actuating means C.

By inserting either tubular member into the lower movable housing portion 45, the interior screw threads 49 will cooperate with the exterior screw threads 61 of the lower tube section 52, holding the two together. It is important that there be a good cooperation of these screw threads so that subsequent rotation of the lower housing portion 45 will also rotate the tubular member.

A carrier 70 for the tubular member 50 is provided, which carrier also supports the lower movable housing portion 45 (since the latter is secured to the tubular member, as has just been detailed) and, in addition, functions as a support for the valve seat, to be described. The carrier 70 has an upwardly directed collar 71, exteriorly screw threaded as at 72 for cooperation with the

screw threads 39 of the cylindrical section 38 of the upper housing portion 30, whereby this portion 30 supports the carrier 70 in a depending position. The upper end of the collar 71, provides a flat surface 73 and at the base of the interior surface of the collar, there is a shoulder 74, below which is an opening through the collar to its lower end 75, which opening is provided with a square screw thread 76 for cooperation with the similar thread 59 of the tubular member 50. There is also provided an exterior shoulder 77 adapted to abut the lower end of the cylindrical section 38, which limits upward movement of the carrier 70. When the carrier 70 is coupled to the upper housing portion 30 and the tubular member 50, connected to the lower housing portion 45, is joined to the carrier 70, as explained, the valve housing appears as in Figures 1, 2, 4 and 14, with the upper end of the cylindrical extension 46 within the circular groove 36. It will be noted, in Figures 4 and 14, that there is a space 78 between the carrier 70 and the lower housing portion 45, with the loose fit of the cylindrical extension 46 within the groove 36 and this space 78, there is communication to the atmosphere from the interior of the valve housing A, so that there will not be apt to be condensation upon the housing A. In order to assist in rotating the lower housing portion 45, a suitable laterally extending handle 79 may be attached thereto or be an integral part thereof. This is the only projection from the housing and there are also no projecting nuts, screw heads or the like.

Disposed upon the shoulder 74 of the carrier 70 is a suitable washer 80, shown in Figure 9, encircling the tubular member 50 and a suitable flow breaker 81 may be inserted into the lower end 62 of the tubular member 50. A suitable resilient means, such as an expansion coil spring 82 may be provided, with one end abutting the valve housing about the boss 40 and its other end bearing upon the valve element, as will be described.

As for the valve seat B, shown particularly in Figure 5, this may be of suitable packing material and presents an inverted truncated conical valve seating surface 90. The outer cylindrical surface 91 of the seat abuts the inner surface of the cylindrical section 38 above the screw threads 39 and extends up to and into the inverted V-shaped groove 35, as in Figures 4 and 14. There is, of course, the usual opening 92 through the seat. A suitable seat carrier for the seat may be provided, shown in Figure 6, comprising a disc 93 with a central opening 94 and a collar 95 about the opening. The seat rests upon this seat carrier with the truncated conical seating surface 90 trending upwardly and outwardly therefrom. The seat carrier rests upon the shoulder 74 of the carrier 70 and it will be noted that there is a space 96 between the washer 80 and the seat carrier.

Any one of the valve elements E, F, G, H, K, L and M may be employed with this novel valve structure. Each comprises a head 100 and depending stem 101 with the head provided with a boss 102 encircled by the lower end of the spring 82, and each has a flattened lower surface 103 about the stem 101. The heads 100 may have solid upper faces as illustrated in Figures 14, 19 and 20, or the heads may be dished, as shown in Figures 18, 22 and 25. In Figure 20 it will be noted that the stem 101 is detachable from the head 100 and the boss 105 is a reduced, projecting end of the stem 101. The stems 101 are of less circumference than that of the opening 54 at the

upper end of the tubular member 50 and, of course, also less than that of the passageways 55 and 57.

Water will not collect in the space 78 and overflow from the upper end of the lower movable housing portion 45 since it will find its way into the recesses 48 and finally flow out of the subordinate opening between the wall of the end 62 of the tube section 52 and that of the nozzle 47.

Upon inserting the spring 82 and a valve element into the stationary housing portion 30, the seat B and its carrier may next be inserted followed by the carrier 70 and washer 80, which former is coupled to the housing portion as has been described, with the valve stem 101 extending through the center of the carrier 70. Then the valve actuating means C or D may be attached as has been described.

By grasping the handle 79 and moving it in an arc, the movable housing portion 45 will rotate and, because of its attachment to the tubular member 50, and the screw threaded attachment of the latter with the carrier 70, will rise. This will cause the valve element to rise and open, and liquid will flow past the seat 90, through the openings 56, through the passageways 55 and 57 and out the outlet 58. Of course, rotation of the movable housing portion 45 in the opposite direction will cause the valve element to fall and close the valve.

Various changes may be made to the forms of the invention herein illustrated and described without departing from the spirit of the invention or scope of the following claims.

What is claimed is:

1. In a valve, a valve element including a valve head and a depending valve stem, a housing including an upper stationary portion provided with a downwardly-opening circular groove; means for actuating the valve element, including a rotatable housing portion, having an open lower end, an upper cylindrical extension disposed within said groove, spaced from the side walls thereof, and spaced from the bottom of said groove when the valve is closed, and a hollow valve element support extending upwardly through and secured to said rotatable housing portion, with the head of said valve element disposed upon the upper end of said support and said stem extending into the hollow of said support and free of attachment with and spaced from said support, said support having exterior screw threads an upper opening

in communication with the interior of said upper housing, when said valve is open, and a lower opening into said open lower end; a depending, hollow stationary carrier secured to said upper stationary housing, disposed within and spaced from the walls of said rotatable housing and provided with interior screw threads, cooperating with said first-named screw threads, and a valve seat supported upon the upper end of said carrier and provided with a bevelled valve head-receiving face.

2. In a valve, a valve element, having a head and stem; a housing comprising a stationary portion having a water inlet, and a rotatable and vertically movable portion having a water outlet, with said portions disposed in telescoping relation; a valve element support carried by said second-named portion, comprising a tube extending through said second-named portion and in communication with said outlet at all times and with said inlet when said valve is open, said tube having exterior screw threads and an upper face upon which said valve head is disposed, and also provided with an opening accommodating said valve stem; a depending stationary carrier carried by said stationary housing portion and extending into said movable housing portion, spaced from the walls of the latter throughout its length, provided with interior screw threads cooperating with said exterior screw threads of said tube; and a valve seat carried by said carrier, said valve element being free of attachment to said tube.

3. In a support means for a reciprocating valve element, said element having a head and a depending stem with the stem free of attachment to said support and adapted to be disposed within a valve housing having interior screw threads, said support means including a tubular body having a substantially flat face at its upper end adapted to support said head, said body provided with a perforation, less in circumference than the inner circumference of said tubular body and greater in circumference than the circumference of said stem, and a perforation in its vertical wall adjacent said first perforation, said tubular body having exterior screw threads cooperating with the interior screw threads of said housing.
